三

A hand-drawn diagram on a whiteboard showing a 4x4 grid of numbered circles (7, 10, 16, ?) and various line segments (parallel lines, diagonal lines, and horizontal lines).

The grid consists of 16 numbered circles arranged in a 4x4 pattern. The numbers are: Row 1: 7, 10, 7, 7; Row 2: 16, 7, 16, 7; Row 3: 7, 7, 10, 7; Row 4: 7, 7, 7, 7. There are also several line segments drawn across the grid, including parallel horizontal lines at the top and bottom, a horizontal line through the center, and several diagonal lines.

UNITED STATES PATENT OFFICE.

LOUIS MICKA, OF ST. LOUIS, MISSOURI.

SCRUBBING-BRUSH.

1,262,539.

Specification of Letters Patent. Patented Apr. 9, 1918.

Application filed July 19, 1917. Serial No. 181,545.

To all whom it may concern:

Be it known that I, LOUIS MICKA, a citizen of the United States, residing at St. Louis, State of Missouri, have invented 5 certain new and useful Improvements in Scrubbing-Brushes, of which the following is a full, clear, and exact description, reference being had to the accompanying drawings, forming a part hereof.

10 My invention has relation to improvements in scrubbing brushes; and it consists in the novel features of construction more fully set forth in the specification and pointed out in the claims.

15 The present invention is particularly directed to brushes for scrubbing concrete floors, walls, and the like, though obviously not restricted in its application. The object of the improvement is to provide a 20 brush (be the same made of bristles or other scrubbing material) to the rubbing face of which may be applied a stream of water with or without a complement of liquid soap or equivalent detergent in liquid 25 or powdered form, suitable provision being made for cutting off the said soap and water supply when no longer needed. A further object is to provide the brush with a flushing attachment whereby the surface or floor 30 when once scrubbed may be flushed with clean water from the same supply source which furnished the water to the brush. The advantages of the invention will be 35 fully apparent from the following detailed description in connection with the accompanying drawings in which—

Figure 1 is a side elevation of my improved scrubbing brush; Fig. 2 is a top plan thereof; Fig. 3 is an enlarged vertical longitudinal section on the zig-zag line 3—3 of Fig. 2; Fig. 4 is an enlarged vertical transverse section on the zig-zag line 4—4 of Fig. 2; Fig. 5 is a bottom plan of the brush-supporting casing detached; Fig. 6 is a vertical cross-sectional detail on the line 6—6 of Fig. 2, the valve bar and valves being in elevation; and Fig. 7 is a cross-sectional detail of the two-way valve controlling the water supply.

50 Referring to the drawings, 1, represents a casing preferably (though not necessarily) rectangular in shape, the same being divided by a horizontal partition wall or dia-

phragm 2 into an upper shot compartment 3, and a bottom water compartment 4, a 55 rubber band 5 encompassing the vertical walls of the casing and serving as a buffer to prevent the scratching of furniture and the wood work about the house. The shot compartment 3 is designed to be filled with 60 shot or lead balls 6 to weight the brush and thus relieve the operator from the necessity of bearing down on the same while scrubbing. The shot is introduced through a charging nipple or opening *o* in the roof 65 of the compartment 3 normally closed by a screw-cap 6. Leading from the bottom of the water compartment 4 are outlet tubes 7 which are inserted through suitable openings designed to receive them in the back or 70 brush mounting 8, the brush in the present embodiment of my invention being in the form of bristles 9 secured to the back 8 in any well approved manner known to the art. The casing 1 is provided with suitable tubular or hollow stays 10, 10' the former (10) spanning the space between the top and bottom walls of the casing and passing through the partition wall 2, the latter (10') being similarly disposed but extending 75 in addition a suitable distance above the top wall of the casing. The upper extension of the longer stay 10' is received by and forms a bushing for, the hollow stay or sleeve 11 connecting the top and bottom 80 walls of a liquid or soft-soap holder or container 12, the soap or other form of detergent being poured into the holder through a filling nipple or opening *o'* normally closed by a screw-cap 13. The stay 10 is traversed 85 by the stem of a suitable bolt 14 the head *h* of which is received in a socket or depression *a* in the bottom of the brush back or mounting 8, the stay 10' receiving the stem of a corresponding but longer bolt 14'. The 90 upper threaded terminal of the bolt 14 is provided with a clamping nut *n* bearing against a washer *w* interposed between it and the top of the casing 1; and the upper end of the bolt 14' receives a nut *n'* bearing 95 against a washer *w'* interposed between it and the top of the soap container 12. The head *h'* of the bolt 14' is likewise received by a socket *a'* in the brush-back 8 (Figs. 3, 4). The bolt 14', thus serves not only to 100 secure and firmly clamp the brush to the

105

casing, but to clamp the soap holder to the casing, and hold the several parts firmly together.

Leading from the bottom of the soap holder are a pair of outlet nozzles 15 which are positioned to enter the upper terminals of the soap feed tubes 16 traversing the casing 1, said tubes passing through the partition wall 2 and discharging into the clearance or space *t* between the bottom wall of the casing (said wall being somewhat raised as clearly shown in Fig. 3) and the top wall of the brush-back 8. From the space *t* the soap flows through the passages 16' formed 10 in the mounting 8 between the bristles 9 (Fig. 3). The flow of the soap through the nozzles 15 is regulated by the reciprocating needle valves 17 depending from the opposite ends of a bar 18 mounted above the soap-holder, the valve stems playing freely 15 through suitable openings provided therefor in the top wall of the soap holder. The bar 18 may be raised or lowered by means of a screw 19 the lower end whereof rests 20 in a socket 20 formed on the top of the soap holder, the stem of the screw in the socket being provided with an annular groove *d* traversed by a set screw *e* passed through 25 the socket wall whereby the screw is prevented from becoming loose. The threaded portion of the screw passes through a boss *i* on the bar 18 to afford a larger purchase 30 to the threads. By turning the screw 19 in proper direction the bar 18 and with it the valves 17 may be raised or lowered, and the flow of the soap through the nozzles 15 be 35 accordingly regulated.

Disposed at the center of the casing 1 and spanning the shot compartment 3 thereof, 40 and discharging directly into the water compartment 4, is a screw-threaded nipple 21 to which is secured an elbow 22. To the elbow 22 is coupled a water delivery pipe 23 serving as a handle for the brush, the 45 upper end whereof terminates in a fitting 24 carrying a valve-casing 25 provided with a two-way valve *V* manipulated by a handle *L*. The casing 25 is provided with a branch tube 26 to which is coupled a flushing hose 50 27 terminating in a nozzle 28, the hose being supported by means of spring clips or clasps 29 carried by the pipe 23. The intake end of the casing 25 receives a short length 55 of pipe 30 to which the water supply hose *H* is directly coupled. The valve *V* is of ordinary construction and may be turned so as to allow the water from the supply hose *H* to flow either into the pipe 23 or into the flush hose 27, or to cut off the water altogether, as clearly obvious from Fig. 7 of the drawings. No claim is made to the valve *per se*.

The operation is clearly obvious from the foregoing, but may be briefly stated as fol-

lows: The valve *V* having been turned to 65 the position shown in Fig. 7, water from the hose *H* flows under pressure through the pipe 23 into the water compartment 4 of the casing 1, thence through the tubes 7 and into the spaces between the bristles 9. 70 The operator at the same time turns the screw 19 sufficiently to raise the bar 18 and valves 17 to uncover the openings leading to the nozzles 15, the liquid soap in the holder 12 flowing through said nozzles 15, 75 tubes 16, space *t* and out through the passages 16' bored in the mounting 8, the water and soap mingling between the bristles and supplying the necessary liquid for cleansing purposes. When the surface has been thoroughly scrubbed, the valves 17 are seated, 80 and the valve *V* turned ninety degrees to admit water into the hose 27, the latter being first detached from the supporting clips 29 (Fig. 2) the hose thus freed being used to 85 flush the cleansed surface of all dirty water and soap. In using the device the compartment 3 is first filled with shot or lead balls *b* so as to weight the casing and brush and relieve the operator as much as possible. 90

I may of course depart in many respects from the details here shown without in any wise affecting the nature or scope of my invention.

Having described my invention what I 95 claim is:

1. In combination with a casing provided with a water compartment having an inlet and a discharge, a bristle brush secured to the casing and traversed by the water discharged therefrom, means on the casing for feeding a suitable detergent to the brush, said detergent mingling with the water as it enters the bristles of the brush, means for cutting off the water supply, and independent means for cutting off the supply of the detergent.

2. In combination with a casing provided with a water compartment and a weight-housing compartment superposed thereover and partitioned therefrom by a suitable division wall, means for passing water into the water compartment through the division wall aforesaid, suitable discharge means for the water compartment, a soap container 115 mounted on the casing, outlet tubes leading from the container through the casing and discharging at points outside the water compartment, a scrub-brush mounted on the casing in position to receive the combined discharges from the soap container and from the water compartment, and independent devices for cutting off the flow from the soap container, and for cutting off the water to the water compartment.

3. In combination with a scrub brush, a casing provided with two superposed compartments for the storage of weights and

for the flow of a stream of water respectively, the water compartment being adjacent the brush, a nipple leading from the water compartment through the top of the 5 casing, means to supply water to the nipple, outlet tubes leading from the bottom of the water compartment, a soap container secured to the casing, valve-controlled means for delivering the soap to the brush, and

means for controlling the stream of water 10 supplied to the nipple.

In testimony whereof I affix my signature, in presence of two witnesses.

LOUIS MICKA.
